UNITED STATES PATENT OFFICE.

MATHEW M. EGAN, OF FORT WORTH, TEXAS.

FOOD-MIXER.

1,095,719.

Specification of Letters Patent.

Patented May 5, 1914.

Application filed November 11, 1913. Serial No. 800,254.

To all whom it may concern:

Be it known that I, MATHEW M. EGAN, a citizen of the United States, residing at Fort Worth, in the county of Tarrant and State of Texas, have invented certain new and useful Improvements in Food-Mixers, of which the following is a specification.

My invention relates to mixing devices for stock feed and particularly to apparatus for mixing large quantities of different kinds of food stuffs to make a composition food, and the object is to provide apparatus by which much time and labor and expense can be saved in mixing the food stuffs and to simplify the mechanism for mixing the food stuffs so that the mixing will be much more simple and easily accomplished.

Another object is to provide apparatus by which the composition food will be uniformly mixed, having a uniform consistency.

Other objects and advantages will be fully explained in the following description and the invention will be more particularly pointed out in the claims.

Reference is had to the accompanying drawings which form a part of this application.

Figure 1 is a diagrammatic elevation of the mixing plant. Fig. 2 is a detail view of a feed pipe. Fig. 3 is a vertical section of the upper portion of the elevator casing, showing a part of the elevating mechanism.

Fig. 4 is a vertical section of the lower part of the elevator casing, showing a part of the elevating mechanism. Fig. 5 is a vertical section of the lower part of a feed chute, showing the mechanism for controlling the discharge of the material.

Similar characters of reference are used to indicate the same parts throughout the several views.

In the drawings, the basement floor of a building is indicated by 1, the second or main floor by 2, and an upper floor by the 3. A main mixing trough 4 is mounted on supports 5. A syrup or molasses tank 6 is provided and a pump 22 is provided for delivering the syrup through the pipe 26 from the tank 6 to the feed pipe 37 which is connected to the discharge nozzle of the pump 22 by the T-pipe 31. The pump 22 is operated by a shaft 23, a cog wheel 24 rigid therewith, a pinion 25 driven by the wheel

24, and a pulley 26 for driving the pinion 25.

When the pump 22 is in operation the molasses will be forced through the feed pipe 37 and it will fall through the perforations 60 in the pipe 37 and fall into the trough 4 to be mixed with the other articles of food. The pipe 26' is provided with a cut-off 27 and if more molasses is forced through the pump 22, the excess will flow through the 65 overflow pipe 48 back into the tank 6. The feed pipe 37 is provided with a regulating cut-off 55.

The food stuffs are fed into different chutes from the main floor 2. Alfalfa is 70 fed into a chute 7. This chute 7 has provision for regulating the amount of alfalfa discharged therefrom. Boards 14 are hingedly connected to the interior of the chute and hang downwardly. These boards are 75 held at the proper angle by screw bolts 15 which are mounted in nuts 49 which are pivotally mounted in the sides of the chute 7. The bolts 15 have swivel connections with the boards 14 and are provided with 80 hand wheels 16. The boards 14 are as wide as the interior of the chute and the material must escape from the lower ends of the boards 14 and the opening or space between these ends can be made as wide or as narrow 85 as desirable, by turning the screw bolts 15 in the proper direction. A spiral conveyer runs in the bottom of the chute 7 for forcing the material out of the spout 50. The conveyer 17 is driven by a cog wheel 18, 90 pinion 19, and power pulley 20.

The advantage of having the boards 14 adjustable is that they can be set for feeding alfalfa ground to different degrees of fineness. Some alfalfa is ground more and 95 is finer than other alfalfa, consequently the boards 14 have to be made adjustable. The boards can be adjusted to feed any required alfalfa to the trough 4.

Oats may be fed through the chute 8 into 100 the trough 4. Cotton seed meal may be fed through the chute 9, bran may be fed through the chute 10, and corn chops may be fed through the chute 11. Agitators of ordinary type may be used in the chutes 105 8, 9, 10, and 11 and these agitators may be driven by the pulleys 21 for feeding material into the trough 4. A salt mill chute 12 is provided for feeding salt to the mill 34. The salt is ground in the mill and fed to 110

the trough 4. The mill 34 is driven by the gear wheel 32.

All of the material is fed to the trough 4, which is provided with a spiral conveyer 28 which is driven by a pulley 29. The material is mixed as it falls into the trough and is forced along by the conveyer 28. The mixed material falls down the chute 40 into the elevator pocket 44. The material is further mixed by running up an elevator.

The elevator 36 has a suitable housing and suitable gearing is provided for elevating the mixed food stuffs. The gearing shown includes sprocket wheels 42 and 43 and the 15 sprocket wheels 43 may be driven by a gear wheel 51. Sprocket chains 41 run on the wheels 42 and 43. Cups 45 are attached to the sprocket chains 41 and run through the pocket 44 to dip up the mixed food stuffs.

20 The food stuffs are delivered by the cups 45 and thrown through a chute 38 into a trough or receiver 52. A spiral conveyer 39 is provided for moving the mixed material in the trough 52 and this conveyer is driven by a pulley 54. As the material is moved along the trough or receiver 52 it is discharged through different spouts 35 and caught in suitable sacks or bags which may be hung 25 on the spouts 35. The end of the trough 30 52 may be left open for overflow if all the material is not fed through the spouts 35 into bags. In order that any material which may escape from the cups near the upper part of the elevator may not be 35 wasted, a board 46 is placed under the sprocket wheels 42 to bridge the space under the wheels and to throw the material into the down leg of the elevator so it will fall back into the pocket 44.

40 It will be seen that means are provided for thoroughly mixing the food stuffs. All the ingredients named may be used or any combination of the ingredients may be used. Any ingredient may be omitted if desirable.

45 The ingredients are mixed as they move or are moved along the trough 4. They are further mixed by the elevator cups which take up the material and dump it into the receiver 52, and they are further mixed by 50 the conveyer 39.

It will be noticed that only one elevator is necessary. This effects a great saving of machinery and labor and the mixing of the material is made thorough. The material 55 or ingredients are more thoroughly mixed than if the ingredients were elevated by separate elevators and then mixed. The labor and expense of operating separate elevators is avoided and fewer men can do 60 the work in much shorter time.

Various changes in the assembling of the parts of the plant can be made without departing from my invention. The feeding of the syrup through pipe 37 may be regulated 65 by a cut-off 55.

What I claim, is,—

1. A mixing apparatus comprising a trough, a series of chutes adapted to discharge material into said trough, agitators in said chutes for discharging material into said trough, a tank and means for conveying syrup from said tank, means for distributing the syrup over material in said trough, means for moving and mixing the material in said trough, a discharge pocket 75 to receive material discharged from said trough, and an elevator provided with a discharge spout at the upper end for removing the mixed material from said pocket.

2. A food mixing apparatus comprising a trough, a series of chutes for feeding material to said trough, means in said chutes for controlling the amount of material fed to said trough, means in said trough for 85 mixing and discharging material therefrom, a pocket for receiving the material from said trough, means for feeding syrup on the material while being moved through said trough, and an elevator provided with a discharge spout at the upper end and including a series of cups for removing the material 90 from said pocket.

3. A food mixing apparatus comprising a trough, a series of chutes provided with 95 spouts adapted to discharge material into said trough, means in said chutes for controlling the feeding of material into said trough, means for agitating and moving the material in said trough, means for feeding 100 a syrup to the material while being mixed including a tank and a pump and a pipe connecting the pump and tank and an open ended perforated pipe for discharging the syrup into said trough, a pocket for receiving 105 the mixed material from said trough, and an elevator provided with a series of cups running through said pocket for further mixing the material and elevating the same.

4. A food mixing apparatus comprising a mixing trough, a series of chutes for feeding different materials to said trough including a chute for feeding a coarse material, boards hinged to the interior of said 115 last mentioned chute and means connected with the chute for varying the position of said boards to regulate the feeding of material therefrom, and means for mixing and discharging material from said trough.

5. A food mixing apparatus comprising a mixing trough provided with a discharge spout, a series of chutes provided with means for discharging different articles of food into said trough, means for distributing a syrup on the mixed articles of food, means in said trough for constantly agitating and moving the material in said trough to the discharge spout, a receiver for said material, an elevator provided with a series 125 130

of cups adapted to run through said receiver for further mixing and elevating said material, a discharge spout at the upper end of said elevator, a distributing trough receiving material from said spout, and means for agitating and mixing the material in said distributing trough.

In testimony whereof, I set my hand in the presence of two witnesses, this 20th day of October, 1913.

MATHEW M. EGAN.
